US0D1079086S

(12) **United States Design Patent** (10) **Patent No.:** **US D1,079,086 S**
(45) **Date of Patent:** **** Jun. 10, 2025**

(54) **LIGHT ASSEMBLY**

- (71) Applicant: **Carhartt, Inc.**, Dearborn, MI (US)
(72) Inventors: **Colleen Hau**, Birmingham, MI (US);
Jonathan West, Ferndale, MI (US);
Saif Islam, Oak Park, MI (US)

(**) Term: **15 Years**

(21) Appl. No.: **29/829,001**

(22) Filed: **Mar. 2, 2022**

(51) **LOC (15) Cl.** **26-05**

(52) **U.S. Cl.**

USPC **D26/85; D26/63**

(58) **Field of Classification Search**

USPC D26/24, 49, 60, 63, 72, 85, 89, 94, 108,

(57) **CLAIM**

The ornamental design for an light assembly as shown and described.

DESCRIPTION

FIG. 1 is a top, front, right side perspective view of a light assembly in a first position, showing our new design;

FIG. 2 is a bottom, rear, left side perspective view of the light assembly in the first position;

FIG. 3 is a front view of the light assembly in the first position;

FIG. 4 is a rear view of the light assembly in the first position;

FIG. 5 is a left side view of the light assembly in the first position;

FIG. 6 is a right side view of the light assembly in the first position;

FIG. 7 is a top view of the light assembly in the first position;

FIG. 8 is a bottom view of the light assembly;

FIG. 9 is a top, front, right side perspective view of the light assembly in a second position;

FIG. 10 is a bottom, rear, left side perspective view of the light assembly in the second position; and,

FIG. 11 is a top, rear right side perspective view of the light assembly in the second position.

The broken lines depict portions of the light assembly that form no part of the claimed design.

1 Claim, 9 Drawing Sheets
